SINGLE-TRIGGER MECHANISM

George E. Larsson, New Haven, Conn., assignor to
Olin Industries, Inc., New Haven, Conn., a cor-
poration of Delaware

Application August 3, 1948, Serial No. 42,238

7 Claims. (Cl. 42—42)

1 The present invention relates in general to firearms and more especially to trigger-mechanisms of that class in which a single trigger is adapted to actuate two or more firing-mechanisms in sequence.

An object of the invention is to provide a superior single-trigger mechanism for a multiple-barrel firearm. A further object of the invention is to provide a multiple-barrel firearm with a relatively-inexpensive compact and dependable trigger-mechanism of the type referred to, constructed with particular reference to safety and adaptability to the firing-mechanisms of existing firearms.

A still further object of the invention is to provide a multiple-barrel firearm with superior trigger mechanism of the type referred to, characterized by inertia-means for automatically selecting the firing sequence of the firearm.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view partly in side elevation and partly in vertical-longitudinal section of the frame-portion of a double-barrel shotgun embodying the single-trigger mechanism of this invention, the two firing mechanisms being shown in their cocked positions;

Fig. 2 is a fragmentary elevation in section on line 2—2 of Fig. 1 showing the right- and left-hand sear-actuators pivotally mounted on the corresponding sears of the fire-control mechanisms;

Fig. 3 is a broken perspective view of the frame-portion of the double-barrel shotgun of Fig. 1 showing the relative positions of the firing-mechanisms and single-trigger mechanism following release of the right-hand firing-pin, the relative positions of the elements of the trigger-mechanism being shown in the positions they have assumed immediately before recoil;

Fig. 4 is a fragmentary perspective view of the single-trigger mechanism of the firearm showing the relative positions of the sear-actuators immediately following recoil of the firearm, the left-hand sear-actuator being moved into position to lock the trigger;

Fig. 5 is a fragmentary perspective view of the trigger-mechanism of the firearm with the

sear-actuators in the positions they assume preparatory to the discharge of the left-hand barrel of the firearm;

Fig. 6 is a detached expanded perspective view of the left- and right-hand sear-actuators; and

Fig. 7 is a perspective view of the trigger.

An exemplary embodiment of the invention is illustrated with the firing-mechanisms and associated parts of a double-barrel breakdown-shotgun, although it will be understood that the invention is applicable to other types of multiple-barrel firearms. Referring to the drawings, the firearm shown herein embodies a frame indicated generally at 10 provided at its upper rear end with a rearwardly-extending tang 11; and on its underside with a trigger-plate 12 having a rearwardly-extending tang-portion 13, to the underside of which is secured a trigger-guard 14.

The forward end of a buttstock, indicated generally at 15, is adapted to be secured between the rear ends of the upper and lower tangs by means of a tie-rod extending longitudinally through the buttstock and threadedly engaged at its forward end in an aperture of a post 16 fixedly mounted between the rear ends of the aforesaid tangs 11 and 13 respectively.

The construction and operation of the locking-mechanism of the firearm are well understood in the art and inasmuch as they are indirectly related to the improved trigger-mechanism of the invention, it is believed that it will suffice to say that the reciprocable locking-bolt 17 of the locking-mechanism is retracted from locking engagement with the barrel-unit 18 of the firearm by means of an eccentric-pin 19 projecting upwardly from the locking-bolt 17 into an eccentric substantially-vertical slot in the left-hand side of the cylindrical bolster 20 of a laterally-swinging top lever 21, the retraction of the locking-bolt 17 by the lateral swinging movement of the top lever 21 permitting the unlocking of the piece for breakdown action in the usual manner of breakdown firearms.

The top lever 21 is adapted normally to hold the reciprocable locking-bolt 17 forwardly in locking engagement with the barrel-unit 18 and to this end a link 22 is provided the shank of which is slidably supported at its rear end in the apertured leg 23 of a bracket 24 fastened to the underside of the upper tang 11, the forward end of the link 22 being offset laterally with respect to the vertical axis of the bolster 20 and engageable in an eccentric-recess 25 in the left-hand side of the shoulder 26 of the bolster 20. A coil spring 27 is carried on the shank of the

link 22, the rear end of the coil spring abutting the leg 23 of the bracket 24, and the forward end of the spring abutting transverse shoulders formed at the forward end of the shank-portion of the link 22. The spring-biased link thus exerts a force moment on the shoulder 26 of the bolster 20 both to effectively resist rotational movement of the top lever 21 in a direction to retract the locking-bolt 17 from locking engagement with the barrel-unit 18, and to automatically return the top lever into barrel-unit-locking position.

The rear end of the bracket 24 is provided with a depending apron-portion 28 having two transversely-spaced substantially-rectangular guide-apertures, the right-hand one of which is indicated at 30, adapted to slidably support the rear end-portions of the substantially-rectangular shanks 31 and 32 respectively of the firing-plungers of the firing-mechanisms. The firing-plungers are indicated generally at 33 and 34 respectively, the forward end of each firing-plunger being reduced in cross section to provide firing-pins 35 and 36 respectively, slidably supported in suitable apertures of the standing-breech 37. Formed on the underside of each firing-plunger is a forwardly-facing cocking-shoulder 38 and 39 respectively, adapted to be engaged by the respective rearwardly-facing shoulders of the sear-notches 40 and 41 of a pair of pivoted sears 42 and 43 respectively, the latter serving to hold the firing-plungers in retracted or cocked position against the force of the firing-plunger springs 44 and 45. As shown especially well in Figs. 1 and 3, the firing-plunger springs 44 and 45 are mounted on the shanks 31 and 32 respectively of the firing-plungers between the front face of the bracket-apron 28 and the rearwardly-facing shoulders 46 and 47 respectively of the firing-plungers.

The bracket 24 also serves as a means for securing the forward end of a leaf spring 48 to the underside of the upper tang 11, the rear end of the leaf spring being slotted longitudinally to form right- and left-hand laterally-spaced substantially-parallel spring-arms 50, each provided with a substantially V-shaped detent 52 respectively. The latter are adapted to cooperatively engage the outer ends of a pin 53 extending transversely through a tongue-member 54 of a safety-slide 55 which is formed on or otherwise secured to the upper end of the tongue 54 for longitudinal sliding movement on the top side of the upper tang 11. The safety-slide 55 is guided for longitudinal movement on the upper tang 11, by engagement of its tongue 54 in a longitudinal slot in the upper tang 11 and is adapted to be held in its rearward or safety "on" position by engagement of the outer ends of its transverse-pin 53 with the rearwardly-facing shoulders of the V-shaped detents 52 of the spring leaf 48; and in its forward or safety "off" position by engagement of the transversely-extending ends of the pin 53 with the forwardly-facing shoulders of the V-shaped detents.

Pivots secured at its rear end to the forward end of the tongue-member 54 of the safety-slide 55 is a safety-slide actuating-bar 56. The latter is slidably supported intermediate its opposite ends in a substantially-vertical slot in the up-standing leg-portion 57 of a bracket 58 suitably secured to the top side of the trigger-plate 12. A pin 59 extends transversely through the vertical slot of the leg-portion 57 of the bracket and engages in a longitudinal slot 60 of the actuating-bar 56 to support the latter in the vertical slot of the bracket and to limit the reciprocable move-

ment of the actuating-bar therein. The forward end of the actuating-bar 56 is adapted normally, that is to say, when the safety-slide 55 is in its "off" position to engage against the rear end of the locking-bolt 17 in which position it is resiliently held by coaction of the pin 53 of the safety-slide with the forwardly-facing shoulders of the V-shaped detents 52. On the other hand, actuation of the top lever 21 to unlock the barrel-unit 18 from the frame 10 as hereinafter described, will displace the locking-bolt 17 rearwardly, positively, and hence move the actuating-bar 56 rearwardly thereby automatically displacing the ends of the safety slide-pin 53 opposite the rearwardly-facing shoulders of the detents whereby the safety-slide 55 is held in its safety "on" position.

Formed on the actuating-bar 56 intermediate its rear end and its longitudinal slot 60, is an integral transversely-projecting lug 61 adapted to engage the upper end of one of the sear-actuators and, in particular, the sear-actuator of the right-hand sear 43 when the safety-slide 55 is in its rearward or safety "on" position, to disconnect the sear 43 from the trigger thereby to positively prevent inadvertent firing of the firearm. However, when the safety-slide 55 is in its normal "off" position, the lug 61 of the actuating-bar 56 is displaced forwardly of the right-hand sear-actuator, as shown especially well in Fig. 1, thereby permitting the latter to cooperatively engage the trigger, as and for the purpose hereinafter described.

Each of the aforesaid sears 42 and 43 comprises a lever-member having a transverse aperture intermediate its opposite ends to receive the corresponding end of the transverse pivot-pin 59 of the bracket 58, each sear being pivotally mounted thus in a vertical slot of the aforesaid leg-portion 57 of the bracket and on opposite sides respectively of the actuating-bar 56. The forward end of each sear is provided with the aforesaid sear-shoulders 40 and 41 respectively, while the rear-end portion of each sear is bent downwardly and provided at its lower extremity with a substantially-horizontal, rearwardly-extending, inwardly-offset fin-portion 62 and 63 respectively. The latter are located in a vertical plane below the underside of the actuating-bar 56 with the inner faces of the respective inwardly-offset fins in substantially mutual engagement, the one fin being slidably vertically past the other.

Each fin 62 and 63 respectively of the aforesaid sears is provided with a transverse aperture in which the inner end of a pin 64 and 65 respectively is secured, the opposite ends of said respective pins extending outwardly transversely for pivotally supporting the respective sear-actuators 66 and 67 of the sears 42 and 43, the sear-actuators being pivotally supported on the aforesaid pins 64 and 65 respectively, substantially vertically. As shown especially well in Fig. 2, each sear-actuator pivot-pin carries a spring 68 and 69 respectively on its outer end, the lower arm 70 of the sear-actuator spring 68 engaging the front edge of the sear-actuator 66 and the upper arm 71 of the sear-actuator spring 68 bearing at its forward end against the underside of the bent-down portion of the sear 42. Similarly, the lower arm 72 of the sear-actuator spring 69 engages against the front edge of the sear-actuator 67, while its upper arm 73 engages beneath the lower edge of the bent-down portion of the sear 43. In accordance with this construction, each sear-actuator 66 and 67 respectively is urged normally to pivot in a clock-

wise direction as seen in Figs. 1 and 3 about its respective pivot-pins 64 and 65 at the rear ends of the sears 42 and 43.

The sear-actuator 66 comprises a blade-like member substantially rectangular in shape, its bottom edge constituting a substantially-square shoulder 74. Formed integrally or otherwise secured to the forward edge of the sear-actuator 66 adjacent the lower end thereof, is an inertia-weight 75 which, as shown especially well in Fig. 3, extends transversely from the left-hand sear-actuator across to the right-hand sear-actuator and is adapted normally to be held against the front edge thereof by the force of its spring 68 whereby the front edges of the actuators lie, normally, in the same transverse plane. The inertia-weight 75 is a solid substantially-rectangular metal block, the underside 76 of which comprises a cylindrical surface of revolution sloping upwardly and forwardly for the purpose hereinafter described.

The sear-actuator 67 is also a substantially-rectangular blade-like member, but is substantially twice the width of the sear-actuator 66 and is provided above its pivot-pin 65 with an upwardly-extending blade-portion 77. The latter lies in the path of the lug 61 of the aforesaid actuating-bar 56 and immediately rearwardly thereof, as a consequence of which the blade-portion 77 is adapted to be engaged and swung rearwardly against the resistance of its spring 69 by the lug 61 when the actuating-bar 56 is moved rearwardly as hereinabove described. The lower end 78 of the sear-actuator 67 is provided with a rectangular notch in its bottom rear corner forming a substantially-square shoulder 79, the latter being in substantially the plane of the bottom edge 76 of the sear-actuator 66, as shown especially well in Fig. 1.

The lower end 78 of the sear-actuator 67 extends below the shoulder 79 of the notch. More particularly, with the sear-actuators 66 and 67 and the trigger 80 of the trigger-mechanisms in their normal firing positions, as shown in Fig. 1, the lower end 78 of the actuator 67 is received in a substantially-vertical clearance-recess 81 which is formed in the top edge 82 of the trigger 80 and extends transversely between opposite sides thereof, the rear wall of the clearance-recess 81 being substantially vertical and forming a stop-shoulder 83. The said stop-shoulder 83 forms a square shoulder 84 with the top edge 82 of the trigger.

Due to the construction and arrangement of the sear-actuators 66-67 as above described, the shoulder 79 of the actuator 67 overlies the shoulder 84 of the trigger and its lower end 78 is normally held in engagement with the stop-shoulder 83 of the trigger. As thus arranged the actuator 67 is normally prevented from being pivoted clockwise by its spring 69 save as will hereinabove appear, and serves by means of the inertia-weight 75 to hold the shoulder 74 of the sear-actuator 66 in its normal inoperative position forwardly of the stop-shoulder 83 of the trigger.

The trigger 80 is pivoted at its forward end in the trigger-plate 12 by a transverse pivot-pin 85 and is adapted to be resiliently held in its normal forward position by a trigger-spring 86, the rearwardly-extending arm 87 of which bears at its lower end against the bottom of a relatively-narrow deep vertical slot 88 formed in the upper edge of the trigger intermediate the opposite sides thereof. As shown especially well in

Fig. 1, the vertical slot 88 intersects the forward end of the trigger and extends rearwardly in the top edge thereof beyond the vertical stop-shoulder 83 of its clearance-recess 81, the depth of the vertical slot 88 being considerably greater than the depth of the clearance-recess 81. The forward arm 89 of the trigger-spring 86 engages at its forward extremity on the top side of the trigger-plate.

10 Referring especially to Fig. 3, formed integrally at the forward end of the trigger and projecting upwardly substantially-vertically of its pivot-pin 85 is an integral vertically-slotted stop-finger 90, the upper ends of which are provided 15 with forwardly-facing beveled surfaces 91 adapted normally to lie in proximity to the upwardly-and-rearwardly-sloping bottom edge 92 of the bracket 58, the sloping bottom edge 92 of which constitutes a fixed abutment adapted to be 20 engaged by the beveled surfaces 91 of the trigger stop-finger to positively limit the rearward movement of the trigger. The back edges of the vertically-slotted stop-finger 90 are formed with arcuate concave surfaces 93 adapted to be 25 engaged by the underside 76 of the inertia-weight 75 when the elements of the trigger-mechanisms are in the positions of recoil, as shown in Fig. 4, the distance from the pivot-pin 64 of the actuator 66 to the underside 76 of its inertia-weight 30 75 being such that the underside of said weight engages the arcuate concave surfaces 93 of the stop-finger 90 forwardly of its pivot-pin 85 thereby to positively prevent the rearward movement of the trigger stop-finger and the concurrent 35 forward movement of the trigger 80 either upon voluntary or involuntary release thereof, immediately following discharge of the firearm.

For a better understanding of the operation of the parts above described, let it be presumed that the elements of the trigger and firing-mechanisms are in the positions they take following the reloading of the firearm and movement of the safety-slide 55 manually forwardly into its safety "off" position, the firing-plungers 33 and 40 34 being held in their retracted cocked positions by the respective sears 42 and 43, the shoulders of which are held up in engagement with the cocking-notches of the respective firing-plungers by coil sear-springs 94 and 95 respectively mounted 45 uprightly in the bracket 58 and engaging at their upper ends against the bottom edges of the respective sears forwardly of the pivot-pin 59 thereof. The compressed firing-springs 44 and 50 45 urge the cocking-notches of the respective firing-plungers forwardly against the respective sear-shoulders 42 and 43 and due to the obliquity of the mutually-engaging surfaces of the cocking-notches and sear-shoulders, the latter are successfully held up in cocking engagement with the 55 firing-plungers. With the sears in cocking engagement with the firing-plungers, the lower forward end of the sear-actuator 67 is resiliently held in engagement with the forwardly-facing substantially-square shoulder 83 of the clearance-recess 81 by the force of the actuator-spring 69, the step 79 of the actuator 67 being disposed in operative position immediately above the square shoulder 84 of the trigger whereby the sear-actuator 67 will be lifted upon rearward 60 draft of the trigger. The sear-actuator 67 is thus positively held from pivoting clockwise, and since the laterally-extending back face of the inertia-block 75 engages against the front edge of the sear-actuator 67, the sear-actuator 66 is 65 effectively prevented from pivoting in a clock-70 75

wise direction, and since the sear-actuator 66 is only substantially half as wide as the sear-actuator 67, the bottom edge 74 of the actuator 66 is held forwardly of the square shoulder 84 of the trigger, that is to say, the sear-actuator 66 is held in an inoperative position with respect to the trigger.

On pulling rearwardly on the trigger 80, the upper edge 82, and more especially its square shoulder 86, is elevated against the substantially-square shoulder 79 of the sear-actuator 67 thereby raising the latter upwardly substantially-vertically whereby the sear 43 is pivoted downwardly in a clockwise direction to disengage its shoulder 41 from the cocking-notch 39 of the firing-plunger 34. The latter is thereupon released and driven forwardly by the force of its compressed spring 45 to discharge a cartridge in the right-hand barrel of the firearm. The positions of the respective elements of the trigger-mechanisms and fire-control mechanisms of the firearm at the instant of firing and prior to recoil are as shown in Fig. 3. That is to say, the sear-actuator 67 is held up in its elevated position by the shoulder 84 of the trigger, while the lower end of the sear-actuator 66 remains below and forwardly of the shoulder 84 of the trigger.

Assuming now that the firearm has recoiled, then the effect of recoil is to swing the inertia-weight 75 of the sear-actuator 66 forwardly, as shown especially well in Fig. 4, thereby moving the underside 76 of the weight 75 into engagement with the back edges 93 of the trigger stop-finger 90. The sear-actuator 66 and its inertia-weight 75 thus constitute a strut-like member which positively prevents the trigger-stop finger 90 from pivoting in a counterclockwise direction. Consequently, the trigger 80 is held in its upward pulled-back position against the force of its flexed spring 88, even though the trigger may be involuntarily released by the shooter's finger on recoil of the firearm. Hence, the forwardly-facing shoulder 83 of the trigger-clearance recess 81 is held up in the path of the lower ends of the spring-biased sear-actuators 66 and 67 whereby each actuator and, more especially, the lower end 78 of the sear-actuator 67, is prevented from being swung clockwise over the upper edge 82 of the trigger into operative relationship with the shoulder 84 thereof by the force of its spring 68. Thus, the subsequent involuntary rearward pull of the shooter's finger on the trigger occasioned by the counter-recoil of the firearm, is effectively prevented from involuntarily firing the cartridge in the second barrel of the firearm. Following the counter-recoil of the firearm and the voluntary release of the trigger, the lower end 78 of the sear-actuator 67 is permitted to swing past the lowered shoulder 83 of the clearance-recess 81 over the upper edge 82 of the trigger rearwardly of its shoulder 84, as shown in Fig. 5. In this position of the actuator 67, its forward edge is moved rearwardly of the aforesaid trigger-shoulder 83 thereby permitting the inertia-weight, together with its sear-actuator 66, to be swung rearwardly by the force of the sear-actuator spring 68 so as to position the lower end 74 of the actuator 66 immediately above and in operative relationship with the shoulder 84 of the trigger. Now, with the elements of the trigger-mechanisms in the positions shown in Fig. 5, on pulling the trigger 80 rearwardly, both the sear-actuator 66 and the sear-actuator 67 will be elevated. Since the sear 43 of the sear-actuator 67 has already released the firing-plunger 34, the

sear 43 will be held downwardly thereby and the elevation of the sear-actuator 67 will have no effect on the firing-plunger 34. On the other hand, elevation of the sear-actuator 66 will lower the shoulder 40 of the sear 42 from engagement with the cocking-notch 38 of the firing-plunger 33 to release the latter and fire the cartridge in the second barrel of the firearm. Immediately following discharge of the second cartridge, the firearm will recoil, but inasmuch as the upper edge 82 of the trigger is engaging against the bottom edge 74 of the sear-actuator 66, the latter is restrained from swinging forwardly and in all probability the sear-actuators will remain in the positions shown in Fig. 5. On releasing the trigger, either voluntarily or involuntarily, the latter will be swung down into its normal position by the force of the flexed trigger-spring 89, the pivoted sear-actuators being held in their rearwardly-displaced positions by the forces of their respective actuator-springs 68 and 69.

To reload the firearm, the top lever 21 is swung to the right and forwardly so as to retract the locking-bolt 17 from the locking-recess in the barrel-unit 18, whereby the barrel-unit may be swung downwardly, as is characteristic of firearms of this type, to open the breech and simultaneously effect the extraction of the fired shells. Simultaneously, the rearward movement of the locking-bolt 17 displaces the actuating-bar 56 rearwardly thereby moving its lug 61 against the blade-portion 77 of the sear-actuator 67 so as to pivot the latter in a counterclockwise direction, whereby the notched lower end of the latter, together with the lower end of the sear-actuator 66, is swung forwardly of the shoulder 84 of the trigger into "safe" positions substantially opposite the clearance-recess 81 thereof, the displacement of the sear-actuators into their respective "safe" positions being accompanied by rearward displacement of the safety-slide 56 to its safety "on" position, as hereinabove described. Now when the barrel-unit 18 is swung downwardly relative to the frame 10, a pair of cocking-links 96 and 97 are actuated in a well-known manner to retract the firing-plungers 33 and 34 and displace the respective cocking-notches 38 and 39 thereof rearwardly of the shoulders 49 and 41 of the respective sears 42 and 43. The latter have been held downwardly heretofore by the released firing-plungers which ride over the forward ends thereof, but on retraction of the firing-plungers the compressed sear-springs 94 and 95 elevate the shoulders of the sears into the paths of the respective cocking-shoulders of the firing-plungers. Consequently, after inserting fresh cartridges into the chambers of the barrel-unit 18 and swinging the latter into its normal closed position, the cocking-links 96 and 97 allow the firing-plungers to advance, as is characteristic of firearms of this class, thereby to re-engage their respective cocking-notches with the corresponding shoulders of the sears. Moreover, the coil spring 27 of the top-lever operating-link 22 automatically rotates the top lever back into its normal position thereby advancing the locking-bolt 17 into locking engagement with the barrel-unit 18. The actuating-bar 56 will remain, however, in its rearward position and hence, in order to discharge the firearm, the operator must manually move the safety-slide 55 forwardly to its safety "off" position, whereupon the actuating-bar 56 will be advanced to its position shown in Fig. 1 thereby releasing the sear-actuator 67 which, urged by the force of its spring 68, pivots clockwise to re-engage its

notched end with the shoulder of the trigger 80, the spring-biased sear-actuator 66 pivoting rearwardly clockwise with the sear-actuator 61 to assume its normal position with respect thereto, as shown in Fig. 1. The firearm is again in readiness for a repetition of the cycle of firing and loading as described above.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a single-trigger mechanism for multiple-barrel firearms, the combination with a pair of firing-mechanisms including a pair of sears: of a trigger; a pair of sear-actuators, each actuator being carried by one of said sears and arranged to be sequentially associated with said trigger with capacity for pivotal movement with respect thereto for actuating the respective sears; and a recoil-actuated element carried by one of said sear-actuators, said recoil-actuated element being engaged normally with the second sear-actuator when said second sear-actuator is in engagement with said trigger to hold said one sear-actuator out of cooperative engagement with said trigger, said recoil-actuated element being arranged to move forwardly on recoil of said firearm and to carry the said one sear-actuator attached thereto forwardly therewith out of position for cooperative engagement with said trigger thereby the firing-mechanisms to be released in a predetermined sequence when said trigger is pulled to discharge said firearm.

2. In a single-trigger mechanism for multiple-barrel firearms, the combination with a pair of firing-mechanisms including a pair of sears: of a trigger having a trigger-stop; a pair of sear-actuators, each actuator being carried by one of said sears and arranged to be cooperatively associated with said trigger with capacity for pivotal movement with respect thereto for actuating the respective sears; and a recoil-actuated element cooperatively associated with one of said sear-actuators to pivot said one sear-actuator forwardly into engagement with said trigger-stop on recoil of said firearm thereby to lock said trigger from involuntary release on recoil of said firearm so as to effect the release of said firing-mechanisms in a predetermined sequence when said trigger is pulled to discharge said firearm.

3. In a single-trigger mechanism for multiple-barrel firearms, the combination with a pair of firing-mechanisms including a pair of sears: of a trigger; a pair of sear-actuators, each actuator being carried by one of said sears and arranged to be sequentially associated with said trigger with capacity for pivotal movement with respect thereto for actuating the respective sears; a recoil-actuated element carried by one of said sear-actuators, said recoil-actuated element being engaged normally with the second sear-actuator when said second sear-actuator is in engagement with said trigger to hold said one sear-actuator out of cooperative engagement with said trigger, said recoil-actuated element being arranged to move forwardly on recoil of said firearm and to carry the said one sear-actuator attached thereto forwardly therewith out of position for cooperative engagement with said trigger.

thereby the firing-mechanisms to be released in a predetermined sequence when said trigger is pulled to discharge said firearm; and resilient-means cooperatively associated with each sear and its corresponding actuator normally to urge said actuators in operative relationship with said trigger.

4. In a single-trigger mechanism for multiple-barrel firearms, the combination with a pair of firing-mechanisms including a pair of pivoted sears and sear-springs arranged to hold said sears in positions for cocking said firing-mechanisms: of a trigger; a pair of sear-actuators, each sear-actuator being pivotally mounted on the rear end of one of said pivoted sears for oscillatory movement in the vertical plane thereof and arranged to be elevated by said trigger for pivoting the respective sears out of cocking engagement with said firing-mechanisms; and an inertia-weight carried by one of said sear-actuators, said inertia-weight being constructed and arranged to hold the said one sear-actuator out of cooperative engagement with said trigger both when the second sear-actuator is in cooperative engagement therewith and upon recoil of said firearm.

5. In a single-trigger mechanism for multiple-barrel firearms, the combination with a pair of firing-mechanisms including a pair of pivoted sears and sear-springs arranged to hold said sears in positions for cocking said firing-mechanisms: of a trigger having a stop-element; a pair of sear-actuators arranged to be engaged by said trigger to pivot the respective sears out of cocking engagement with said firing-mechanisms, said respective sear-actuators being pivotally mounted on the rear ends respectively of said pivoted sears for oscillatory movement in the vertical plane thereof; and an inertia-weight carried by one of said sear-actuators to pivot said one sear-actuator forwardly into engagement with said trigger-stop on recoil of said firearm thereby to lock said trigger from involuntary release on recoil of said firearm so as to effect the release of said firing-mechanisms in a predetermined sequence when said trigger is pulled to discharge said firearm.

6. In a single-trigger mechanism for multiple-barrel firearms, the combination with a pair of firing-mechanisms including a pair of pivoted sears and sear-springs arranged to hold said sears in positions for cocking said firing-mechanisms: of a trigger having a stop-element; a pair of sear-actuators arranged to be engaged by said trigger to pivot the respective sears out of cocking engagement with said firing-mechanisms, said respective sear-actuators being pivotally mounted on the rear ends respectively of said pivoted sears for oscillatory movement in the vertical plane thereof; an inertia-weight carried by one of said sear-actuators to pivot said one sear-actuator forwardly into engagement with said trigger-stop on recoil of said firearm thereby to lock said trigger from involuntary release on recoil of said firearm so as to effect the release of said firing-mechanisms in a predetermined sequence when said trigger is pulled to discharge said firearm; and resilient-means cooperatively associated with each pivoted sear and its corresponding pivoted sear-actuator normally to hold said pivoted sear-actuators in operative relationship with said trigger.

7. In a single-trigger mechanism for multiple-barrel firearms, the combination with a pair of firing-mechanisms including a pair of pivoted sears and sear-springs arranged to hold said sears in positions for cocking said firing-mechanisms:

11

of a trigger having a stop-element; a pair of sear-actuators arranged to be engaged by said trigger to pivot the respective sears out of cocking engagement with said firing-mechisms, said respective sear-actuators being pivotally mounted on the rear ends respectively of said pivoted sears for oscillatory movement in the vertical plane thereof; an inertia-weight carried by one of said sear-actuators to pivot said one sear-actuator forwardly into engagement with said trigger-stop on recoil of said firearm thereby to lock said trigger from involuntary release on recoil of said firearm so as to effect the release of said firing-mechisms in a predetermined sequence when said trigger is pulled to discharge said firearm; resilient-means cooperatively associated with each pivoted sear and its corresponding pivoted sear-actuator normally to hold said pivoted sear-actuators in operative relationship with said trigger; and manually-operated safety-means arranged to be cooperatively associated with one of

5

12

said pivoted sear-actuators to pivot said one sear-actuator forwardly against the resistance of its resilient-means into inoperative position with respect to said trigger.

GEORGE E. LARSSON.
